UNITED STATES PATENT OFFICE

1,967,886

SAWHORSE

Ralph W. Johnson, Minneapolis, Minn.

Application March 20, 1933, Serial No. 661,679

2 Claims. (Cl. 304—6)

My invention provides an improved device of the type generally designated as a sawhorse, but which is capable of a wide range of use and is especially adapted for use to support the boards 5 of a scaffold or the like.

Generally stated, the invention consists of the novel devices, and combinations of devices hereinafter described and defined in the claims.

The improved sawhorse involves various novel 10 features whereby the legs thereof can be folded against the rail or top beam and can be vertically extended to support the rail at various distances from the floor as may be required to properly support scaffolding or the like.

15 A commercial form of the device is illustrated in the accompanying drawing wherein like characters indicate like parts throughout the several views.

Referring to the drawing:

20 Fig. 1 is a perspective showing the improved sawhorse;

Fig. 2 is a fragmentary section taken on the line 2—2 of Fig. 1;

Fig. 3 is a section taken on the line 3—3 of

25 Fig. 2;

Fig. 4 is a fragmentary perspective showing lower portions of one of the legs and its leg extension;

Fig. 5 is a section taken on the line 5—5 of

30 Fig. 4;

Fig. 6 is a section taken on the line 6—6 of

Fig. 1; and

Fig. 7 is a perspective showing in detail one of the leg-anchoring hinge brackets.

35 The rail or top beam 8 is preferably made from a wooden plank and to the underside of the ends thereof are rigidly secured, by screws or other suitable devices, leg-anchoring hinge brackets 9 that are preferably stamped from sheet metal.

40 These brackets 9, at their outer ends, are formed with laterally spaced depending hinge lugs 10 and at their inner ends they are formed with curled sleeve-forming portions 11 and projecting lips 12, which latter, when screws or the like are passed therethrough into the rail 8, securely anchor the 45 inner end portions of said brackets.

The legs 13, which are preferably of angle iron or steel, are pivotally connected at their upper ends to the lugs 10 and are rigidly tied together in 50 pairs by metallic tie plates 14 that are welded or otherwise rigidly secured to the inwardly projecting flanges of the respective legs and are thus spaced from the outer flanges of said rails, as best shown in Fig. 2, thus leaving spaces for the 55 sages of leg extension bars 15. These bars 15

are preferably square steel rods that fit into the angles of the respective legs 13. At their lower ends, the flanges of legs 13 are provided with in-turned lips or portions 16 that loosely embrace and hold the leg extensions for sliding movements 60 only.

The extreme lower ends of the leg extensions 15 are turned outward to afford feet 17 that may, in some instances, be secured to the floor by nails or screws passed therethrough, and into the floor. 65 To hold the leg extensions in various different vertical adjustments, the legs 13 are shown as formed in their ridges with holes 18 through which and holes in the leg extensions 15 pins or lock devices such as split keys 19 are arranged to 70 be passed, as best shown in Figs. 1 and 3.

The leg structures just noted are thus connected so that each forms a sort of A-frame structure. The lower edges of the tie plates 14 are turned inward and projected so as to form shelf-supporting ledges 20 upon which the ends of a shelf 21, preferably a wooden board, is adapted to be placed. As shown, the tie plates 14 are provided with inwardly bent lips 22 arranged to immediately overlie the ends of the shelf 21. Also the 80 tie plates 14 are shown as formed with projecting lips 23 between which the ends of the shelf 21 will be placed and held against edgewise displacement when the legs are set up. At their upper portions, the tie plates 14 are provided with inwardly projecting ears or lugs 24. To brace and hold the legs firmly in set up positions, I provide 85 braces, preferably and as shown, in the form of bail-like metal rods 25 hingedly mounted in the sleeve portions 11 of the brackets 9 and provided 90 with in-turned free ends 26 that are arranged to be engaged through perforations in the lugs 24 and held in such engagement by the spring tension in the said braces, except when force is applied tending to separate the legs of the said 95 braces.

Fig. 1 shows the sawhorse set up for use and it will be noted that in such condition of the parts, the leg structures are very firmly braced by the braces 25 and the shelf 21 will be held against accidental displacement, inasmuch as the ends are caged between the ends 20 and lips or projections 22 or 23 of the said tie plates. Of course, when the ends of the braces 25 are sprung out of engagement with the lugs 24, the shelf 21 will be 100 readily dropped from position and the leg structures may then be folded against the bottom of the rail 8.

The fact that the legs of the device are capable of very considerable longitudinal adjustment, 105

adapts the device for use to support scaffolding in proper position for a workman, having respect to the height of the ceiling or other structure that is being worked upon. The knock-down or fold-up feature adapts the sawhorse to be stored in small space and to be easily carried or shipped from place to place.

In actual practice, the device has been found to be highly efficient for the various purposes had in view, and can be made at comparatively small cost and is very strong and durable.

What I claim is:

1. A sawhorse comprising a top rail, hinge brackets secured to the bottoms of said rail, said brackets at their outer ends having spaced hinge lugs and at their inner ends having bearing

sleeves, legs pivoted to the lugs of said brackets and diverging downwardly therefrom, tie plates rigidly connecting said legs in pairs and having spaced ears, and bail-like oblique braces pivotally mounted in the bearing sleeves of said brackets and provided with laterally projecting ends detachably engaged through the ears of said tie plates.

2. The structure defined in claim 1 in which said tie plates are provided with inwardly projecting shelf-supporting ledges, and a shelf detachably engageable with said ledges and held in position when said legs are set in rail-supporting position.

RALPH W. JOHNSON.
